United States Patent Office

Des. 216,512

Patented Jan. 27, 1970

216,512

DRINKING FOUNTAIN BUBLER

Rimas J. Geleziunas, 43 Saintfield Ave.,
Don Mills, Ontario, Canada

Filed May 27, 1968, Ser. No. 12,097

Term of patent 14 years

Int. Cl. D23—01

U.S. Cl. D23—34

FIG. 2

FIG. 1

FIG. 3

FIG. 4

The dominant features of my design reside in the portions shown in full lines.

I claim:

The ornamental design for a drinking fountain bubbler, as shown and described.
